UNITED STATES PATENT OFFICE.

WILLIAM C. P. COLLIGNON, OF OREGON, ILLINOIS, ASSIGNEE TO SCHILLER PIANO COMPANY, OF OREGON, ILLINOIS, A CORPORATION OF ILLINOIS.

TRACKING DEVICE FOR AUTOMATIC MUSICAL INSTRUMENTS.

1,260,968.

Specification of Letters Patent. Patented Mar. 26, 1918.

Application filed September 19, 1914. Serial No. 862,421.

To all whom it may concern:

Be it known that I, WILLIAM C. P. COLLIGNON, a citizen of the United States, residing at Oregon, in the county of Ogle and State of Illinois, have invented a certain new and useful Improvement in Tracking Devices for Automatic Musical Instruments, of which the following is a full, clear, concise, and exact description, reference being 10 had to the accompanying drawings, forming a part of this specification.

My invention relates to tracking devices for automatic musical instruments, such as player pianos and the like.

Prominent objects of the invention are to provide a simple and practical tracking device by which the traveling music sheet or similar instrumentality may be automatically shifted laterally with respect to its direction of movement; to arrange for the automatic restoration of the traveling music sheet or similar device to normal position, shifting it in either lateral direction as required to maintain its proper location; to 25 simplify the mechanism and secure a high degree of efficiency; and to secure the foregoing and other desirable results in a simple and practical manner.

In carrying out my invention as herein-after set forth I arrange a device which is capable of engaging the two opposite edges of the music sheet and is capable of movement in a direction transverse to the direction of travel of the music sheet, as caused by a shifting of the latter. This sheet operated device is arranged in connection with pneumatic mechanism whereby the movement of the device in one direction or the other operates said pneumatic mechanism so as to automatically return the music sheet to its proper normal position.

The mechanism herein shown may, of course, be used for other purposes.

In the accompanying drawings Figure 1 is a front elevation of a tracking device embodying my present invention;

Fig. 2 is a horizontal sectional view showing a portion of the mechanism;

Fig. 3 is a sectional view showing a detail of construction; and

Figs. 4 and 5 are views showing more particularly the sheet shifting mechanism.

Referring to the drawings I show in Fig. 1 a horizontal support 1 which is understood to be a supporting member in the construction of a player piano or like device. From this rises uprights 2 and 3 between which is extended a cross bar 4, the whole forming a frame for the music sheet 5. This music sheet is mounted on the usual rolls 6 and 7 carried by spindles 8 and 9, respectively. A sliding rod 10 is mounted to slide longitudinally in the uprights 2 and 3, the longitudinal movement of said rod being transverse to the direction of movement of the music sheet 5. Said rod is provided with collars or projections 11 and 12 separated from one another substantially the width of the music sheet 5, whereby said projections or lugs will engage the opposite side of the music sheet. The rod 10 is extended beyond the upright 3 and has a projecting end 10^a which is connected with a valve rod 13 which extends down to and is connected with a valve 14. This valve works in guide-ways 15 and rests upon a valve block 16, (Fig. 3), which is provided with three ports 17, 18 and 19. The central port 18 is connected with a duct 20 which is understood to be connected by a tube 21 (Fig. 1) with the pressure reducing apparatus. The two side ports 17 and 19 are connected with tubular members 21^a and 22, respectively which extend to the opposite sides of a pneumatic power device 23 having two pneumatic members 24 and 25 operating a common walking beam 26. The walking beam 26 is connected with a rod 27 which extends downwardly and is connected with a crank arm 28 on a long rod 29 which extends back of the music frame to the right hand side of the music spools where its right hand end is provided with a crank arm 30. This crank arm 30 is connected with a rod 31, which extends to and is pivotally connected with another rod 32, which extends to the bearing for the upper roll spindle 8, to which bearing said rod 32 is rigidly and firmly connected. A sleeve or collar 33 is secured rigidly to the middle frame member or support 34 and is provided with a cam slot 35 in which the rod 32 may travel. Another rod 36 extends down from the swinging end of the rod 32 and is pivotally connected with a swinging

rod 37 which extends to and is rigidly connected with the bearing for the lower music roll spindle 9. Another cam collar 38 is secured to the middle upright 39, the rod 37 being arranged to move in a spiral cam groove in said collar 38 similar to the cam groove 35 in the collar 33.

Thus it will be seen that a movement of the music sheet 5 to one side or the other will cause a movement of the valve 14, thereby affecting the condition or relation of the ports 17 and 19 to the central port 18. A movement of the valve 14 to the left, (Fig. 3) will cause the port 17 to be connected with the port 18 and the port 19 to be shut off therefrom. A movement of said valve 14 to the right will have the opposite effect. When said valve 14 is moved in this way connection is established through one or the other of the ducts 21 and 22, and thereby to one side or the other of the compound pneumatic in the device 23. When the valve 14 is moved to the left and the port 17 connected with the port 18, the left hand pneumatic 24 will be exhausted, causing a collapsing movement on the part of said pneumatic, and a corresponding expanding movement on the part of the pneumatic 25. When the valve 14 is moved in the opposite direction the pneumatic 25 will have a collapsing movement and the pneumatic 24 an expanding one. The operation of the walking beam or swinging member 26 causes an actuation of the rod 27 and a partial rotation of the rod 29 and actuation of the rod 31 by the crank 30. This in turn will cause a movement of the rods 32 and 37 and a shifting movement of the spindles 8 and 9 in an axial direction. When the pneumatic 24 is collapsed and the pneumatic 25 expanded the rod 27 will rise causing an upward movement on the part of the cranks 28 and 30 and consequently an upward movement on the part of the rod 31 and an upward swinging movement on the part of the rods 32 and 37. This movement will cause the rods 32 and 37 to move in their cam grooves in a direction to the right, referring to Figs. 1 and 4. Thus the music sheet is automatically shifted to the right which is a movement of restoration to normal position, the movement which caused the collapse of the pneumatic 24 having been a movement of the valve 14 to the left as caused by a movement to the left on the part of the music sheet 5. In a similar way a movement of the valve 14 to the right will cause a collapse of the pneumatic 25 and a corresponding downward movement on the part of the rod 27 and the crank arms 28 and 30, and a downward swinging movement on the part of the rods 32 and 37 which will cause a movement to the left on the part of the music sheet 5, thereby restoring the same to normal or central position. The rod 13 may

be adjusted relatively to the rod 10 by means of a screw 12^a, whereby an adjustment of the valve 14 relative to the rod 12 and the position of the music sheet 5 may be secured.

It will be understood that changes and modifications may be made without departing from the spirit of the invention.

What I claim is:

1. A tracking device comprising a member adapted to engage the opposite side edges of the traveling music sheet, a valve actuated by said member, a valve block having three ports controlled by said valve, the central port being connected with a source of reduced pressure, a bellows arrangement having two pneumatics connected with said other two ports, and means whereby said bellows arrangement causes an actuation of the traveling music sheet in a direction transverse to its direction of motion. 75

2. A tracking device comprising a member adapted to engage the opposite side edges of the traveling music sheet, a valve actuated by said member, a valve block having three ports controlled by said valve, the central port being connected with a source of reduced pressure, a bellows arrangement having two pneumatics connected with said other two ports, and means whereby the music sheet is automatically restored to normal position by the actuation of said bellows arrangement. 90

3. A tracking device comprising a member adapted to engage the opposite side edges of the traveling music sheet, a valve actuated by said member, a valve block having three ports controlled by said valve, the central port being connected with a source of reduced pressure, a bellows arrangement having two pneumatics connected with said other two ports, and means whereby said bellows arrangement causes an actuation of the traveling music sheet in a direction transverse to its direction of motion, said mechanism comprising rod connections to the music spool spindles and cam sleeves on said spindles having cam grooves co-operating with said rod connections. 100 105

4. A tracking device comprising a member adapted to engage the opposite side edges of the traveling music sheet, a valve actuated by said member, a valve block having three ports controlled by said valve, the central port being connected with a source of reduced pressure, a bellows arrangement having two pneumatics connected with said other two ports, and means whereby the music sheet is automatically restored to normal position by the actuation of said bellows arrangement, said mechanism comprising a rod connected with said bellows arrangement, another rod having a crank connected with said first mentioned rod and also having its other end provided 110 120 125 130

with another crank, a third rod connected with said last mentioned crank, rods secured to the music spool spindles, another rod connected with said music spool spindle rods, 5 and also with said rod connected with the last mentioned crank, and cam collars rigidly secured in position surrounding said music spool spindles, said collars having cam grooves in which said music spool spin-
10 dle rods may work.

5. The combination of a slidable rod provided with projections adapted to engage the opposite sides of a music sheet, a valve having a rod connected with said first men-
15 tioned rod, a valve block having three ports to be controlled by said valve, whereof the central port is connected with a source of reduced air pressure, and a double bellows device having its opposite sides connected
20 with the side ports in said valve block.

6. The combination of a slidable rod provided with projections adapted to engage the opposite sides of a music sheet, a valve having a rod connected with said first men-
25 tioned rod, and a valve block having three ports to be controlled by said valve, whereof the central port is connected with a source of reduced air pressure.

7. The combination of a slidable rod provided with projections adapted to engage the opposite side edges of a music sheet, another rod having an adjustable connection with said first mentioned rod, a valve carried by the second mentioned rod and a
35 valve block on which said valve slides.

8. The combination of a slidable rod provided with projections adapted to engage the opposite sides of a music sheet, a valve having a rod connected with said first men-
40 tioned rod, a valve block having three ports to be controlled by said valve, whereof the central port is connected with a source of reduced air pressure, and a double bellows device having its opposite sides connected
45 with the side ports in said valve block, said bellows having a connection whereby both ends of the sheet are moved in synchronism.

9. The combination of a slidable rod provided with projections adapted to engage
50 the opposite sides of a music sheet, a valve having a rod connected with said first men-

tioned rod, a valve block having three ports to be controlled by said valve, whereof the central port is connected with a source of reduced air pressure, and a double bellows 55 device having its opposite sides connected with the side ports in said valve block, said bellows having a connection whereby both ends of the sheet are moved in synchronism, said connections including a cam provided
60 adjacent one end of the spindles of the music sheet.

10. The combination of a slidable rod provided with projections adapted to engage the opposite sides of a traveling music sheet, 65 said rod having a valve secured to one end thereof, and means whereby said valve controls the movement of said sheet in opposite directions, said means including pneumatics, connections from said valve to said pneumatics, and means for moving said sheet transverse to the direction in which said music sheet travels.

11. The combination of a slidable rod provided with projections adapted to engage 75 the opposite sides of a traveling music sheet, said rod having a valve secured to one end thereof, and means whereby said valve controls the movement of said sheet in opposite directions, said movement being trans-
70 verse to the direction in which said music sheet travels.

12. The combination with a tracker bar, of means for effecting a relative adjustment 80 between the tracker bar and a music sheet 85 in a direction transverse to the direction of travel of the music sheet, said means including a device engaging the music sheet so as to be moved in one direction or another by a lateral deviation of the sheet, a valve and 90 a valve port member having three ports in a row, said valve being adapted to connect the middle port with either end port, and being connected with said device so as to be moved in opposite directions thereby.

In witness whereof, I hereunto subscribe my name this 14th day of September A. D. 1914.

WILLIAM C. P. COLLIGNON.
